Ralph W. Foster

UNITED STATES PATENT OFFICE.

FRANK L. WOLFE, OF MEDFORD, MASSACHUSETTS, ASSIGNOR TO THE CROSBY STEAM GAGE AND VALVE COMPANY, OF BOSTON, MASSACHUSETTS.

PRESSURE-RECORDER.

SPECIFICATION forming part of Letters Patent No. 665,154, dated January 1, 1901.

Application filed March 14, 1900. Serial No. 8,644. No model.

To all whom it may concern:

Be it known that I, FRANK LESLIE WOLFE, a citizen of the United States, and a resident of Medford, in the county of Middlesex and 5 State of Massachusetts, have invented certain new and useful Improvements in Pressure-Recorders, (Pen-Lever,) of which the following is a specification.

My invention relates to pressure-recorders, 10 and more particularly to the pen-lever, being an improvement upon my invention described in Letters Patent of the United States dated May 3, 1898, No. 603,391; and its object is to provide for the adjustment of the pen-lever 15 to the chart over which it moves. I accomplish this by means of the device illustrated in the accompanying drawings, in which similar letters refer to similar parts throughout.

Figure 1 represents a recorder in perspective, showing the adjusting device attached to the upright cylinder of the same. Fig. 2 is an enlarged plan view showing the top of the cylinder, the pen-lever as attached to it, the adjusting device, and a section of the 25 chart and its platform. Fig. 3 shows a cross-section of the pinion which operates the adjusting device.

A is a plate attached to the top of the cylinder D by screws *a a*. From the outer end 30 of this plate there depends a stud B, within which is arranged the pinion-rod *b*, surmounted by the pinion *b'*, and terminating at its lower end in the knurled piece *b*³, employed to turn it.

35 *b*³ is a binding-screw adapted to engage the groove *b*⁴ of the pinion-rod.

To the top of the plate A is pivotally attached the sector C by the screw *c*. This sector engages at its gear end *c*³ the pinion *b'*, and at its other end it is made with a slot *c*', which straddles the piston-rod F below the ball *f*. The pen-lever K, which carries the pen *k*, is pivotally attached at one end to the stud L and is actuated by the piston-rod F. 45 The cylinder is attached to the recorder, and the apparatus is inclosed in the recording-case in the usual manner.

The operation of my device is as follows: The cylinder D is or may be of the general 50 type described in said Letters Patent, having

mounted upon it a pen-lever K, adjustably and pivotally fulcrumed at L and actuated by the piston-rod F, which engages it by means of a slot or groove in the ball *f* running in the direction of the pen-lever. Heretofore it has been necessary to adjust the pen to the chart by moving it to or from the chart with the fingers and then fixing it in place. This method has proved unsatisfactory and difficult, as the adjustment is a very delicate 60 one. By my device the necessary micrometric adjustment is easily obtained. The pen-lever being properly fulcrumed at L and in engagement with the top of the piston-rod, the pen being in place, and the piston-rod being in engagement with the slotted portion of the sector, as explained, I turn the pinion-rod by means of the knurled end, and thereby rotate the sector, which carries the piston-rod toward or away from the chart, thereby 70 carrying the pen attached to the outer end of the pen-lever to or away from the chart. When the adjustment is made, the pinion-rod may be fixed by means of the binding-screw *b*³. 75

Having described my invention, what I claim, and desire to secure by Letters Patent, is—

1. In a pressure-recorder the combination; with the cylinder D, piston-rod F and pen-lever K mounted on said cylinder and actuated by said piston-rod; of the sector C mounted on said cylinder, and the pinion *b'* to engage the gear end of the sector; together with means for rotating the pinion, and means for locking it; substantially as described. 80

2. In a pressure-recorder the combination; with the cylinder D, piston-rod F and pen-lever K mounted on said cylinder and actuated by said piston-rod; of the sector C mounted on said cylinder, and the pinion *b'* to engage the gear end of the sector; together with means for rotating the pinion; substantially as described. 90

3. In a pressure-recorder the combination; with a cylinder and a piston-rod and a pen-lever mounted on said cylinder and actuated by said piston-rod; of a sector mounted on said cylinder and having a slot in one end to engage said piston-rod, and a pinion to en- 100

gage the gear end of the sector; together with means for rotating the pinion, and means for locking it; substantially as described.

4. In a pressure-recorder the combination; with a cylinder and a piston-rod and a pen-lever mounted on said cylinder and actuated by said piston-rod; of a sector mounted on said cylinder and having a slot in one end to engage said piston-rod, and a pinion to engage the gear end of the sector; together with means for rotating the pinion; substantially as described.

5. In a pressure-recorder the combination; with a cylinder and a piston-rod and a pen-lever mounted on said cylinder and actuated by said piston-rod; of a lever mounted on said cylinder and having one end adapted to

engage said piston-rod; together with means for actuating said lever, and means for locking it; substantially as described.

6. In a pressure-recorder the combination; with a cylinder and a piston-rod and a pen-lever mounted on said cylinder and actuated by said piston-rod; of a lever mounted on said cylinder and having one end adapted to engage said piston-rod; together with means for actuating said lever; substantially as described.

In testimony whereof I have affixed my signature in presence of two witnesses.

FRANK L. WOLFE.
